CLAIM

The ornamental design for a jar of a portable blender, as shown and described.

DESCRIPTION

FIG. 1 is a front view of a jar of a portable blender, showing the new design;

FIG. 2 is a rear view thereof;

FIG. 3 is a side view thereof;

FIG. 4 is a top view thereof;

FIG. 5 is a bottom view thereof;

FIG. 6 is a front perspective view thereof; and,

FIG. 7 is a rear perspective view thereof.

The broken lines in the drawings are for showing portions of the jar of a portable blender that forms no part of the claimed design.

1 Claim, 7 Drawing Sheets# US D1,085,814 S
